WELL HEAD INSERT

James H. Howard and Yeager L. Markins, Houston, Tex., assignors to J. H. McEvoy & Company, a corporation

Application December 16, 1931, Serial No. 581,302

27 Claims. (Cl. 166—15)

The invention relates to an improvement in well head equipment wherein a combination blowout preventer and pipe support is adapted for insertion in the well head, either for emergency use or for use in connection with the usual operations in and about the well.

It is one of the objects of the invention to provide an insert for the well head which is adapted to seal the area between the casing and a pipe which may be positioned therein.

Another object of the invention is to provide an insert which is adapted to be quickly moved into position by mechanical means so that injury to the operator will be avoided.

Another object of the invention is to provide a blowout preventer which is adapted to be moved both laterally and vertically by mechanical means so that it will clamp about a pipe positioned in the well casing.

Another object of the invention is to provide a packing assembly for insertion in the casing head by mechanical means which will cause the packing assembly to close about the pipe when being moved into position and to open to release the pipe when being withdrawn from position.

A still further object of the invention is to provide a supporting structure for a well head insert such that the insert may be moved to operative or inoperative position by the mechanical means.

It is also an object of the invention to provide a resilient pressure connection for a packing assembly so that the same will move to closed position when it engages the pipe about which it is to be positioned.

Other and further objects of the invention will be readily apparent when the following description is considered in connection with the accompanying drawings wherein:

Fig. 1 is a side elevation of a well head equipped with the invention, and showing the casing head broken away to illustrate the internal construction thereof.

Fig. 2 is a top plan view of the structure shown in Fig. 1.

Fig. 3 shows a modified form of the invention with the device in an inoperative position.

Fig. 4 is a diagrammatic view of the invention of Fig. 3 with the packing assembly inserted in the well casing.

Fig. 1 shows a casing indicated generally at 2 which is preferably the surface casing which is anchored to the earth and which forms a part 55 of all well equipment. Positioned on this casing

2 is a casing head 3 which is provided with the outlets 4 and 5. The upper portion of this casing head is tapered to form a bowl 6 which is arranged to receive the blowout preventer or packing element 7. In order to support the structure embodied in this invention, a supporting ring 8 has been provided and this ring is shown as being threaded at 9 to the top of the casing head 3 so that it will serve as a suitable support for the blowout preventer mechanism. It is contemplated that this ring 8 may be flanged to the casing head if a flanged connection is provided on the casing head.

The ring 8 carries a table or supporting plate 11 which extends laterally from the axial plane of the casing head. This table has mounted thereon a standard 12 which carries a bearing 13 to receive the transverse shaft 14. The shaft 14 is mounted for movement in the bearing 13. The shaft 14 serves as a support for a rack 15 and a pinion 16 which serves as a mechanism for moving the blowout preventer 7. The rearward movement of the rack 15 is limited by the stop rod 18 which is pivoted to the table 11 at 19 and passes through the opening 20 in a bracket 21 carried by the end of the rack 15. The opening 20 is somewhat larger than the rod 18 so that when the rack moves forward or to the left as viewed in Fig. 1 the rod 18 will slide freely through the opening 20. The nut 22 is provided to adjust the movement of the rack 15 and to limit the rearward movement thereof. The rack 15 is shown as being slidably mounted in the housing 25 which is mounted on the shaft 14. The pinion 16 is mounted to rotate on top of the housing 25 and a hand wheel 26 is provided to rotate this pinion. It is understood that rotation of the pinion causes longitudinal movement of the rack 15 to cause a similar movement of the blowout preventer 7. The housing 25 is pivoted so that the blowout preventer may be closed to engage the seat 6 in the casing head, Fig. 4 showing the invention in operative position.

The blowout preventer 7 is seen in open position in Fig. 2 and comprises a plurality of segments 30 which are mounted upon a supporting rod 31. This rod is connected to the segments 30 by a yoke 32, the ends of which pass loosely through an eye 33 which is carried by each of the segments 30. The rod 31 is slidably mounted in a recess 35 in the end 36 of the rack member 15. A coil spring 37, however, is provided to support against the end of the rack member and against a collar 38 positioned on the rod 31. In this

manner the rod 31 is capable of limited sliding movement independently of the rack member 15, so that there will be no injury to the segments 30 if excessive pressure is applied to the rack member 15 after the blowout preventer has been seated because if the rack moves beyond its normal position such movement will be absorbed by the rod 31 telescoping into the recess 35, and thereby compressing the spring 37. It should also be noted that the eyelets 33 are positioned on each side of the point of pivoting of the segments 30 so that when the blowout preventer, as seen in Fig. 2, moves forwardly to engage the pipe, the points 40 thereof will be the first to engage the pipe at a point such as 41. Obviously, when this heel or corner 40 engages the pipe the forward movement of the rod 31 will be practically terminated. Due to the positioning of the eyelets 33 however, continued movement of the rack member 15 causes a pressure to be exerted by the spring 37 upon the rod 31 and accordingly upon the yoke 32 inasmuch as the eyelets 33 are positioned on each side of the point of contact 40 with the pipe. It is apparent that any further pressure tends to move tips 42 of the segments 30 toward each other so that the blowout preventer will clamp around the pipe.

In addition to the rod 31 the links 45 are provided which connect with the plates 46 mounted on each of the segments 30. These links 45 are also connected to a bracket 47 carried by the head of the rack member 15 and are each arranged for swinging movement in this bracket 47 by being passed thru an opening 48 which is somewhat larger than the size of the link. The links are also mounted to swing with respect to the plates 46 by passing loosely through the eye blocks 49. These links 45 tend to create a pull or a push on the blowout preventer upon movement of the rack member so that the blowout preventer will be moved easily to operative or inoperative position.

The pivotal connection of the links with the blowout preventer and with the rack member permits the opening and closing of the blowout preventer, and due to the fact that the spring 37 normally urges the yoke or head 32 forwardly causes the eyelets 49 to move to extended position so that the blowout preventer will normally remain in the position shown in Fig. 2. Thus the preventer is normally open and ready to be moved about the pipe. To accomplish this movement it is only necessary to rotate the hand wheel 26 to move the rack 15 and slide the blowout preventer over to a position to engage about the pipe.

The pipe in the well is indicated at 50 and is provided with the usual coupling 51. When it is desired to retain the blowout preventer in the well head by the weight of the string of pipe 50, the preventer can be moved forwardly until the lower end thereof moves into the casing head opening whereupon the entire mechanism will pivot about the shaft 14 so that the blowout preventer will drop into the bowl 6 as seen in Fig. 4. The string of pipe may then be lowered so that the coupling 51 will seat on top of the segments 30 and expand the packer so that a seal will be obtained between the casing head and the pipe.

If it is desired to retain the blowout preventer in sealing position without positioning the coupling 51 thereon or utilizing the weight of the string of tubing, a series of dogs or locking segments 52 have been provided in a groove 53 in the top of the blowout preventer. These dogs

are movable radially of the blowout preventer and are arranged to engage with the teeth or projections 54 formed on the inside of the support ring 8. The arrangement of dogs in a blowout preventer or packing head is shown in the patent 5 to J. H. McEvoy, 1,867,321, granted July 12, 1932.

When the blowout preventer is to be removed from the seat 6, it will be accomplished by, first, retracting the teeth 52 with a suitable wrench from the complementary ratchet teeth of 54, 10 then raising the pipe 50 until the next collar below 51 on the string comes in contact with the bottom of the blowout preventer and raises it out of the bowl. With the blowout preventer resting on the collar and out of the casing head, it 15 may be drawn back to inoperative position as shown in Fig. 1, by turning the handwheel 26 reverse to the operation of putting it in.

When the rack 15 is moved back to the position shown in Fig. 1, the eye 21 comes in contact 20 with nut 22, and any further backward movement of rack 15 causes the apparatus to pivot about shaft 14. This pivoting causes the blowout preventer to be lifted from contact with plate 11. This lifting action is advantageous because it allows the blowout preventer to hang vertically, which is the proper position for having it ready to be placed around the pipe. The apparatus, Figs. 1 and 2, has been made and tested, and has been found to work perfectly in whatever position the pipe might be in. The apparatus will not clamp around a collar, nor can it be made to jam in an ineffective manner by the collar. Also if the operator is careless in pulling the blowout preventer out of the head, he cannot damage it by pulling it too high. With the construction shown, after the insert has been raised up a distance, it will slide off of the shoulder of the collar and drop down, and then by turning the handwheel it can be drawn back to operative 40 position.

It has been found necessary to have loose joints to make operation possible in any position of the pipe. Taper on the lower end of blowout preventer is a necessary feature for centralizing the pipe as the blowout preventer is forced into the head. It is to be understood that the pipe 50 does not hang at all times concentric with the casing, but it may be touching one side, thus being off center.

It has been found that this inserter is positive in operation, economical to make, centralizes the pipe automatically, allows easy changing of the blowout preventer for different sizes of pipe, and can stand very rough handling without jamming.

It also is to be understood that this apparatus may be used for handling slips for gripping and holding the pipe, instead of a blowout preventer by merely substituting a set of slips for the insert 7.

Figs. 3 and 4 show a somewhat modified form of the invention which is substantially identical with the Fig. 1 showing, except in the mechanism used to move the blowout preventer. In Fig. 3 this mechanism is shown as a cylinder 80 which carries a piston 81 which in turn connects to a piston rod 82. The piston rod 82 is the same as the rack member 15 and supports the rod 31 and the links 45 in a manner the same as the rack member 15.

In order to cause movement of the shaft 82 within the cylinder 80, the fluid pressure lines at 84 and 85 are provided. The flow of fluid to these lines is controlled by a valve 86 which is known as a four-way valve, and serves to connect 75

either one of the lines 84 or 85 with the inlet line 87 or with the exhaust line 88. It will be noted that in both forms of the invention the shaft 14 is so seated with respect to the extensible means that the operating mechanism tends to counterbalance the packing element.

Fig. 4 shows the invention of Fig. 3 with the piston rod 82 extended so that the blowout preventer has moved over to engagement with the pipe and has dropped into the seat 6. One of the particular advantages of the present invention is that the packer or blowout preventer may be moved into position about the pipe very quickly, and when it is apparent that a blowout is imminent the valve 86 or the hand wheel 26 may be quickly operated to move the packer about the pipe. The driller can then drop the pipe so that a coupling will engage the top of the packer and the well will in this manner be sealed. With devices now in use it is necessary for one of the workmen to place the packer in position in the casing head and then the driller can lower the pipe so that a coupling will engage the packer. It often occurs that the workman is injured by the coupling dropping on his hand, or in some other manner. The operation of the present invention is positive and insures proper positioning of the packer or blowout preventer at all times.

Having described our invention, what we claim as new is:

1. An insert for well heads including an insert head composed of a plurality of hinged segments adapted to fit about a pipe, a rod supporting said segments, links connected to said segments, and means to which said rod and links are connected to move said insert head toward and away from the pipe.

2. An insert for well heads including an insert head composed of a plurality of hinged segments adapted to fit about a pipe, a rod supporting said segments, links connected to said segments, and movable means to contact said segments with the pipe whereby said links will move said segments around the pipe.

3. An insert for well heads including an insert head composed of a plurality of hinged segments adapted to fit about a pipe, a rod supporting said segments, links connected to said segments, and means to which said rod and links are connected to move said insert head toward and away from the pipe, said rod being slidably mounted in said means.

4. An insert for well heads including an insert head composed of a plurality of hinged segments adapted to fit about a pipe, a rod supporting said segments, links connected to said segments, and means to which said rod and links are connected to move said insert head toward and away from the pipe, said rod being connected to two of said segments.

5. An insert for well heads including an insert head composed of a plurality of hinged segments adapted to fit about a pipe, a rod supporting said segments, links connected to said segments, and means to which said rod and links are connected to move said insert head toward and away from the pipe, said rod being slidably mounted in said means, said rod being connected to the adjacent sides of said segments and said links being connected to said segments so that shortening of said rod causes said links to move said segments together.

6. A closure for well heads including a packing head composed of segments, a rod upon which said segments are pivotally connected, means to

slidably support and move said rod laterally of the well head, and additional means connecting said segments and said first means whereby sliding of said rod with respect to said first means causes pivoting of said segments.

7. In combination with a well casing, a casing head thereon, a pipe passing therethrough, a unitary well head insert mounted on said casing head, means connected to said insert to move said insert toward and away from said pipe, said means adapted to close said insert about said pipe when said insert comes in contact with said pipe, and means on said casing head to contact said insert to hold said insert in locked relation with said casing head when said insert is positioned in said casing head.

8. An insert for well heads including an insert head composed of a plurality of hinged segments adapted to fit about a pipe, links connected to said segments, a rod connected to two of said segments, said rod being resiliently forced against said head connection to hold said insert head open.

9. An insert for well heads including an insert head composed of a plurality of hinged segments adapted to fit about a pipe, means to force said insert head laterally of said pipe, links pivotally connecting sides of said segments to said forcing means, resilient means between said links bearing on adjacent segments to hold said insert head open when not closed about a pipe.

10. An insert for well heads including an insert head composed of a plurality of hinged segments adapted to fit about a pipe, means to move said insert from open position away from said pipe to closed position about said pipe, said means including links connected to sides of said insert head, and resilient means for holding said insert open when in open position, and said moving means including a double acting cylinder.

11. An insert for well heads including an insert head composed of a plurality of hinged segments adapted to fit about a pipe, means to move said insert from open position away from said pipe to closed position about said pipe, said means including links connected to sides of said insert head, and resilient means for holding said insert open when in open position, and said moving means including rack and pinion.

12. An insert for well heads including an insert head composed of a plurality of hinged segments adapted to fit about a pipe, means to move said insert from open position away from said pipe to closed position about said pipe, said means including links connected to sides of said insert head, and resilient means for holding said insert open when in open position, said moving means including a double acting cylinder, said cylinder being pivotally mounted.

13. An insert for well heads including an insert head composed of a plurality of hinged segments adapted to fit about a pipe, means to move said insert from open position away from said pipe to closed position about said pipe, said means including links connected to sides of said insert head, and resilient means for holding said insert open when in open position, said moving means including rack and pinion, and said moving means being pivotally mounted.

14. An insert for well heads including an insert head composed of a plurality of hinged segments adapted to fit about a pipe, means to move said insert from open position away from said pipe to closed position about said pipe, said means including links connected to sides of said insert

- head, and resilient means for holding said insert open when in open position, said moving means including a double acting cylinder, said cylinder being pivotally mounted, and said moving means being pivotally mounted.
5. 15. An insert for well heads including an insert head, a pipe, means to position said insert head about said pipe, said means being pivotally mounted, and arranged to elevate said positioning means.
10. 16. An insert for wells including an insert head, a well casing, an inner pipe, pivoted extensible means for positioning said insert head about said inner pipe, means on said insert head to lock said head into the top of said well casing.
15. 17. A well casing, a casing head thereon, a pipe passing therethrough, a packing insert adapted to form a seal between said casing head and said pipe, means whereby said insert head may be moved from an open position away from said pipe to a closed position about said pipe, said means being disposed to counterbalance said head in open position.
20. 18. An insert for wells including a well casing, an inner pipe, an insert head composed of a plurality of segments adapted to fit about a pipe, means attached to the sides of said segments whereby said head may be moved toward and away from said pipe whereby said head serves as a support for said pipe, when about the pipe and in said casing.
25. 19. A well casing, a casing head thereon, a pipe passing therethrough, a packing insert adapted to form a seal between said casing head and said pipe, means whereby said packing insert may be moved from an open position away from said pipe to a closed position about said pipe, said means including a pivot to lower said insert into said casing, and a releasable latch to hold 30 said packing insert in sealing position.
30. 20. A well casing, a casing head thereon, an inner pipe, an insert head adapted to fit about a pipe and within said casing head, means attached to said insert head to move said head to contact said pipe whereby said head will close about the pipe, and interengaging locking means on said heads to retain said insert head in closed position.
35. 21. In combination with a well casing, a casing head thereon, a pipe passing therethrough, a well head insert associated with said casing head, means connected to said insert head to move said insert head toward and away from said pipe, said means being adapted to close 40 said insert about said pipe when said insert comes in contact with said pipe, and means on said casing head engaged by said insert to hold said insert in fixed relation with said casing head when said insert is positioned in said casing head.
45. 22. In combination with a well casing, a casing head thereon, a pipe passing therethrough, an insert head adapted to seat in said casing head and around said pipe, said insert head comprising a plurality of tapered pipe engaging segments, and a support for said insert head having connections thereto adapted to move said insert head toward said pipe, one of said connections being yieldable and normally holding said 50 insert head in an open position.
50. 23. In combination with a well casing, a casing head thereon, a pipe passing therethrough, an insert head adapted to seat in said casing head and around said pipe, said insert head comprising a plurality of packing elements, and an extensible support for said insert head having connections thereto adapted to move said insert head toward and away from said pipe, one of said connections being yieldable and normally holding said 55 insert head in an open position.
55. 24. In combination with a well casing, a casing head thereon, a pipe passing therethrough, an insert head adapted to seat in said casing head and around said pipe, said insert head comprising a plurality of packing elements, and an extensible support for said insert head having connections thereto adapted to move said insert head toward and away from said pipe, one of said connections being yieldable and normally holding said 60 insert head in an open position, the other of said connections acting to close said segments about said pipe when same is engaged.
60. 25. In combination with a well casing, a casing head thereon, a pipe passing therethrough, an insert head adapted to seat in said casing head and around said pipe, said insert head comprising a plurality of packing elements, an extensible support for said insert head having connections thereto adapted to move said insert head toward and away from said pipe, one of said connections being yieldable and normally holding said 65 insert head in an open position, and means to secure said insert head in said casing head.
65. 26. In combination with a well casing, a casing head thereon, a pipe passing therethrough, an insert head adapted to seat in said casing head and around said pipe, said insert head comprising a plurality of packing elements, and an extensible support for said insert head having connections thereto adapted to move said insert head toward and away from said pipe, one of said connections being yieldable and normally holding said 70 insert head in an open position, the other of said connections acting to close said segments about said pipe when same is engaged, and means to lock said insert head in closed position in said casing head.
70. 27. An insert for wells including a well casing, a casing head thereon, a pipe passing therethrough, an insert head adapted to fit between said casing head and said pipe, to seal said casing head, means pivoted to move said insert to and from said pipe, whereby said insert head will 75 move vertically and horizontally.
